(57) **ABSTRACT**

A heat transfer tube (1) with a finned inner surface, which is divided into at least two zones (Z_1 to Z_m) in peripheral direction. The fins (2, 3), which extend at an angle of inclination α with respect to the longitudinal axis of the tube, are arranged in the individual zones (Z_1 to Z_m) in any desired periodic combination and sequence of at least two fin heights (H_1 to H_n , $H_1 > H_2 > \dots > H_n$). Adjacent zones border thereby on one another so that the fin sequence is staggered for at least one fin in longitudinal direction of the tube. Modifications include the finned inner surface being divided into groups of zones, in which the angle of inclination of the fins is uniform, however, varies between adjacent groups.

**INTERNALLY FINNED HEAT TRANSFER
TUBE WITH STAGGERED FINS OF
VARYING HEIGHT**

FIELD OF THE INVENTION

The invention relates to a heat transfer tube having an inner surface structure. The heat transfer tube is suited in particular for the evaporation of liquids from pure materials or mixtures on the inside of the tube. However, it also offers advantages for the condensation of vapors.

BACKGROUND OF THE INVENTION

A world-wide competition in the field of heat exchangers, for example fin-tube heat exchangers (compare FIG. 1) for air-conditioning and refrigeration, demands high-performance heat transfer tubes, which are produced using little material (thus resulting in a low weight of the tube) and inexpensively in few tube forming steps. The heat transfer tubes are inserted into fin-tube heat exchangers, which can often be reversed between evaporation and condensation, and the tubes are thereby installed mostly horizontally into the fin-tube heat exchangers.

The state of the art includes a heat transfer tube according to:

- (a) U.S. Pat. No. 5,332,034, in which during two successively occurring roll embossing steps fins of a uniform height are first roll embossed onto a strip, and during a second step notches are formed into the fins. The material displaced from the fins is thereby moved laterally of the fins into the troughs. The two-step fin forming process demands several embossing tools, which are arranged in series, and thus is less economical. In addition this two-step fin forming process does not achieve a reduction of the weight of the tube in spite of the forming of the notches. The notches in adjacent fins are aligned so that a second predestined flow direction in direction of the aligned notches results near the wall in addition to the troughs, which extend parallel to and between the fins. This second preferred direction serves indeed the transverse exchange between the troughs of the first-mentioned preferred direction, the additional creation of turbulence and the increase of the evaporation performance. However, on the other hand the existence of a second preferred direction makes the desired formation of a spiral flow in the area near the wall more difficult.
- (b) DE-A-196 12 470, in which on the inner surface parallel and alternating (or also intersecting one another) high and low fins with notches additionally cut into the fins are formed. The notches of adjacent fins are here also aligned.
- (c) DE-A-196 28 280, in which in peripheral direction of the tube the alignment of the fins is alternated in sections between two different directions. A spiral flow cannot form here due to the missing preferred direction and in contrast to the helix-shaped structures. This form of the structuring of the inner surface has proven to be little suited during evaporation since clearly lower evaporation performances are achieved than with tubes having a surface which provides a clear preferred direction for the flow near the wall. Whereas during condensation this type of surface structuring has proven to be advantageous.
- (d) JP-A 4/158 193, in which in peripheral direction of the tube a differentiation is made in sections between areas

of low and high fin heights. Of course, in addition to the first preferred direction in direction of the aligned fin elements a second one extending in longitudinal direction of the tube beyond the small fins is constructed, which very negatively influences in particular the evaporation performance since the flowing fluid is no longer necessarily forced into a spiral flow wetting also the upper half of the tube, but simply flows off in axial direction along the sections of lower fin height and above and beyond these small elements.

SUMMARY OF THE INVENTION

The purpose of the invention is to provide a heat transfer tube having an inner surface structure which combines the advantages of an evaporation performance, which is good or improved in comparison to the state of the art, and simultaneously has a reduced tube weight compared to the state of the art, and a reduced production expense effected by a reduction in the number of roll embossing steps.

The purpose is attained according to the invention in heat transfer tubes by the fins of each individual zone (Z_1 to Z_m) being arranged in longitudinal direction of the tube in any desired periodic combination and sequence of at least two fin heights (H_1 to H_n , $H_1 > H_2 > \dots > H_n$) and extending at an angle of inclination with respect to the longitudinal axis of the tube, whereby adjacent zones (Z_1 to Z_m) border one another so that at the transition of two zones the fin sequence is staggered with respect to one another for at least one fin in longitudinal direction of the tube.

This results in the following advantages of the invention:
(1) Due to the alternating change between high and low fins in their longitudinal direction the possibility of a transverse exchange between the channels is offered over the fins of low height with a corresponding additional creation of a turbulence. However, the staggered arrangement of the fins of low height avoids a second and interfering preferred direction similar to the aligned arrangement of the notches disclosed in U.S. Pat. No. 5,332,034.

(2) A clear preferred direction of the flow near the wall exists precisely so that with the thus forced spiral flow a complete wetting of the entire tube circumference and especially of the upper half sections of the inner tube surface, is achieved. The wetting is needed for a good and improved evaporation performance. Whereas in the case of structures without a uniform preferred direction, as disclosed in DE-A-196 28 280, a drying of the upper sections of the tube circumference occurs and consequently a significant reduction of the evaporation performance.

(3) In contrast to the subsequent forming of the notches in a second embossing step, this structure can be created in one single embossing step so that, instead of the displacement of material out of the fins into the troughs, indeed a material savings and a weight reduction is achieved and in addition a reduction of the production expense through a reduction in the number of fin forming steps.

(4) Structures with an angle of inclination of the fins varying in zones offer mainly, with respect to the technique of shaping, important advantages since possibly occurring lateral forces, which are caused by the grooves and fins extending at an incline with respect to the direction of the strip, can be at least partially compensated for in the fin forming process, and the guiding of the strip is in this manner made easier. The

heat transfer performance can be further increased by the edges, sharp-edge or also rounded projections and recesses, which edges are according to the invention provided additionally in the surface structure through the various heights, base widths, and cross-sectional shapes of the fins of varying height.

Through the various heights, base widths, and cross-sectional shapes of the fins of varying height additional edges, sharp-edge or also rounded projections and recesses are created in the surface structure and in the lateral flanks of the near wall troughs, which edges, projections and recesses serve to create a further turbulence and, in particular in the case of mixtures, to prevent the possible formation of temperature and concentration boundary layers and yet be available as additional nucleation sites. (Advantage over DE-A-196 12 470).

The manufacture of the heat transfer tube of the invention is based, for example, on the method described in greater detail hereinafter. Copper or a copper alloy are usually used as the material for the heat transfer tubes, however, the present invention is not limited in this manner. Rather any type of metal can be used, for example aluminum. A metallic flat strip is initially subjected to a one-step embossing step by being guided between an emboss roll with a surface design complementary to the structure of the invention and a support roll. One side of the flat strip receives thereby the structure of the invention, whereas the second side remains smooth or has also a structuring here not described in detail. Merely the strip edge areas of the first side, which edge areas are used for the subsequent welding, may possibly be differently structured or may even remain non-structured. The structured flat strip is after the embossing step formed into an open seam tube, is seam welded, and the tube, if necessary, receives in addition during a final drawing process the desired outside diameter. A possible influence on the heat-transfer ability of the heat transfer tube of the invention by the strip edge area, which surrounds the welding seam and which may be differently structured or remains even non-structured, is unimportant and can be neglected.

In the preferred embodiment of an emboss roll for the manufacture of the heat transfer tubes of the invention, the modular design of the emboss roll out of disks or rings is a further advantage of the invention. The design enables according to the modular concept a quick set-up and evaluation of many structure variations within the scope of a test scheme and a quick adaptation of the surface structuring to new fluids and changed operating conditions through a change of the number, form and (groove) geometry of the disks and rings or through the exchange of individual disks/rings.

BRIEF DESCRIPTION OF THE DRAWINGS

The invention will be discussed in greater detail in connection with the following exemplary embodiments.

In the drawings:

FIG. 1 illustrates a fin-tube heat exchanger according to the state of the art,

FIG. 2 is a perspective drawing of a section of an internally finned heat transfer tube,

FIG. 3 is a schematic top view of an inventive heat transfer tube with an opened-up, finned inner surface,

FIG. 4 illustrates in an enlarged scale a cross section perpendicular with respect to the fin centerlines of one high and one low fin according to FIG. 3,

FIG. 5 is a schematic top view of an inventive heat transfer tube analogous to FIG. 3, in which the high and the low fins are each separated from one another by a gap,

FIG. 6 schematically illustrates the design of an emboss roll for the manufacture of the inventive heat transfer tube,

FIG. 7 is a black-white illustration of a top view of an inventive heat transfer tube with an opened-up inner surface, which is divided into four zones,

FIG. 8 illustrates an inner surface according to FIG. 7, in which the high and the low fins are each separated by a gap,

FIG. 9 is a black-white illustration of a top view of a further inventive heat transfer tube with an opened-up inner surface, which is divided into six zones, whereby the fins have positive and negative angles of inclination, and

FIG. 10 is a black-white illustration of a top view of a further inventive heat transfer tube with an opened-up inner surface, which is divided into six zones, whereby the fins have a different angle of inclination in the two center zones than the fins in the two respective edge zones.

DETAILED DESCRIPTION

FIG. 1 illustrates a fin-tube heat exchanger according to the state of the art with horizontally arranged heat transfer tubes 1 having fins not identified in detail.

FIG. 2 illustrates a longitudinal section of a heat transfer tube 1 having an outer diameter D, which tube 1 is welded and, therefore, has a longitudinal seam 11. The heat transfer tube has a smooth outer surface and a structured inner surface.

FIG. 3 schematically illustrates a top view of the opened-up inner surface of such a finned heat transfer tube 1. The inner surface is divided into four zones (Z_1 to Z_4) extending in longitudinal direction of the tube (see the direction of the arrow). High fins 2 (fin height H_1) and low fins 3 (fin height H_2) are alternatingly (in longitudinal direction of the tube) formed into each zone (Z_1 to Z_4), which fins are separated by grooves 4. The fins 2, 3, and the grooves 4, extend at an inclination with respect to the longitudinal direction of the tube, namely the centerlines 5 of the fins 2, 3 form with the longitudinal direction of the tube an angle of inclination α . Adjacent zones (Z_1 to Z_4) are staggered so that a respective high fin 2 and a low fin 3 abut at the borders of the zones (Z_1 to Z_4). The fin length within one zone, measured along the centerlines 5 of the fins 2, 3, is identified by the letter L.

FIG. 4 illustrates in detail the fin pitch t (distance from fin center to fin center, measured perpendicularly with respect to the fin centerlines 5), the fin apex angle γ_1 or γ_2 , the fin height H_1 or H_2 , and the fin base widths F_1 or F_2 . The apex angles γ_1 , γ_2 and the base widths F_1 , F_2 are also measured in a cross-sectional plane perpendicular with respect to the fin centerlines 5.

FIG. 5 illustrates schematically and analogously to FIG. 3 a top view of the opened-up inner surface of a finned heat transfer tube 1, in which high and low fins are separated from one another at the transition of adjacent zones each by a gap 12 having a length B (measured along the extended centerlines 5 of the fins 2, 3).

FIG. 6 schematically illustrates the design of an emboss roll 6 for the manufacture of the heat transfer tube 1.

The roll 6 is assembled of various disks 7, which are staggered in peripheral direction. Deep and less deep grooves 8, 9 are alternatingly cut into the individual disks 7, which grooves 8, 9 produce during rolling of the roll 6 on the sheet-metal strip 10 in one embossing operation the high fins 2 and the lower fins 3 in the individual zones Z_1 to Z_5 . The sheet-metal strip 10 is after the structuring has been completed formed into an open seam tube and is thereafter longitudinally welded to produce the welding seam 11.

FIGS. 7 to 10 illustrate in black and white further embodiments of the invention, whereby the fin tips/fin flanks are white and the base of the grooves 4 extending between the fins 2, 3 is black.

FIGS. 7 and 8 each illustrate an embodiment having four zones (Z_1 to Z_4), whereby FIG. 8 is different due to the additional arrangement of gaps 12 having the length B between the high fins 2 and the low fins 3. These relationships are made clear by the illustration according to FIG. 5.

The inner surface of the heat transfer tube 1 according to FIG. 9 is divided into 6 zones (Z_1 to Z_6). The fins 2, 3 extend in the group G_1 consisting of three zones (Z_1 to Z_3) at the angle of inclination α , in the group G_2 consisting of three zones (Z_4 to Z_6) at the (negative) angle $\alpha'=-\alpha$, which angle is symmetrically opposite with respect to the boundary line between adjacent groups.

The inner surface of the heat transfer tube 1 according to FIG. 10 is also divided into 6 zones (Z_1 to Z_6). The fins 2, 3 extend in the groups G_1 and G_3 consisting of zones Z_1/Z_2 and Z_5/Z_6 at the angle of inclination α , in the group G_2 consisting of zones Z_3/Z_4 at a different angle of inclination $|\alpha'| \neq |\alpha|$.

NUMERICAL EXAMPLE

For the manufacture of a heat transfer tube 1 with an outer diameter of $D=7$ mm, the emboss roll 6 is designed with 19 disks 7 having a diameter of 33 mm and a thickness of 1.2 mm so that the resulting structuring of the inner surface of the heat transfer tube 1 corresponding to FIG. 2 consists of nineteen (19) 1.2 mm wide zones prior to the final drawing process, in which zones alternating high and lower fins 2, 3 (alternating in longitudinal direction of the strip 10) extend at an angle of $\alpha=14.3^\circ$ with respect to the longitudinal direction of the flat strip 10. In this embodiment, each zone contains, in a cross section in peripheral direction, exactly one high and one lower fin 2, 3 so that altogether in peripheral direction nineteen (19) high fins 2 and nineteen (19) lower fins 3 are created. The fin heights are $H_1=0.14$ mm and $H_2=0.07$ mm, the apex angle $\gamma=45^\circ$, the lengths of the fins $L=4.86$ mm and the pitch (the distance between a high and a low fin measured perpendicularly with respect to the fin) is $t=0.58$ mm. To effect a staggering of the zones or respectively a staggering of the disks 7 of the emboss roll 6 a twist angle between adjacent disks of 90° is set.

What is claimed is:

1. A heat transfer tube having a finned inner surface, which is divided into at least two zones (Z_1 to Z_m) in peripheral direction, the zones bordering adjacent ones of the zones in a longitudinal direction along the length of the inner surface, whereby individual fins having varying fin height extend at an angle of inclination with respect to a longitudinal axis of the tube, wherein the fins spaced apart in the individual zones (Z_1 to Z_m) are arranged in any desired periodic sequence of at least two fin heights (H_1 to H_n , $H_1 > H_2 > \dots > H_n$), whereby adjacent zones (Z_1 to Z_m) border one another so that at a transition of two adjacent ones of the zones the fin height changes for at least one of the fins.

2. The heat transfer tube according to claim 1, wherein in each of the zones (Z_1 to Z_m) in the periodic sequence exactly one of the fins with the fin height H_i ($i=1$ to n) is followed by one of the fins with the fin height H_j ($j=1$ to n , $j \neq i$, $H_j \neq H_i$) and further ones of the fins with the height H_k ($k=1$ to n , $k \neq i$, j , $H_k \neq H_i$, H_j) along the longitudinal direction of the tube.

3. The heat transfer tube according to claim 1, wherein in each of the zones (Z_1 to Z_m) in the periodic sequence two or more separate spaced fins with the fin height H_i ($i=1$ to n) are

each followed exactly by another one of the separate spaced fins with the fin height H_j ($j=1$ to n , $j \neq i$, $H_j \neq H_i$) in the longitudinal direction of the tube.

4. The heat transfer tube according to claim 1, wherein in each of the zones (Z_1 to Z_m) in the periodic sequence exactly one of the separate fins with the fin height H_i ($i=1$ to n) is followed by two or more separate spaced ones of the fins with the fin height H_j ($j=1$ to n , $j \neq i$, $H_j \neq H_i$) in the longitudinal direction of the tube.

5. The heat transfer tube according to claim 1, wherein in each of the zones (Z_1 to Z_m) in the periodic sequence two or more of the separate fins with the fin height H_i ($i=1$ to n) are followed by two or more of the fins with the fin height H_j ($j=1$ to n , $j \neq i$, $H_j \neq H_i$) in the longitudinal direction of the tube.

6. The heat transfer tube according to claim 1, wherein an outer tube diameter of D is from 3 mm to 20 mm, the angle of inclination α is from 5° to 85° , the largest fin height H_1 is from 0.05 mm to 0.5 mm and the fin length per zone L is from 0.5 mm to 15 mm.

7. The heat transfer tube according to claim 6, wherein an outer tube diameter D is from 6 mm to 12.7 mm, the angle of inclination α is from 100 to 400, the largest fin height H_1 is from 0.1 mm to 0.3 mm and the fin length per zone L is from 0.5 mm to 10 mm.

8. The heat transfer tube according to claim 1, wherein the fin heights H_j ($j=2$ to n) compared with the largest fin height H_i , define a ratio H_j/H_i from 0.1 to 0.9.

9. The heat transfer tube according to claim 2, wherein the fin height H_2 , compared with the largest fin height H_i , results in a ratio H_2/H_1 from 0.2 to 0.7.

10. The heat transfer tube according to claim 3, wherein the fin height H_2 , compared with the largest fin height H_i , results in a ratio H_2/H_1 from 0.2 to 0.7.

11. The heat transfer tube according to claim 4, wherein the fin height H_2 , compared with the largest fin height H_1 , results in a ratio H_2/H_1 from 0.2 to 0.7.

12. The heat transfer tube according to claim 5, wherein the fin height H_2 , compared with the largest fin height H_1 , results in a ratio H_2/H_1 from 0.2 to 0.7.

13. The heat transfer tube according to claim 6, wherein the fin height H_2 , compared with the largest fin height H_1 , results in a ratio H_2/H_1 from 0.2 to 0.7.

14. The heat transfer tube according to claim 7, wherein the fin height H_2 , compared with the largest fin height H_1 , results in a ratio H_2/H_1 from 0.2 to 0.7.

15. The heat transfer tube according to claim 1, wherein the fin pitch t is from 0.1 mm to 0.8 mm and the apex angle γ_1 to γ_n is from 10° to 60° .

16. The heat transfer tube according to claim 15, wherein the fin pitch t is from 0.2 mm to 0.6 mm and the apex angle γ_1 to γ_n is from 20° to 50° .

17. The heat transfer tube according to claim 1, wherein the cross sections of the fins are geometrically different.

18. The heat transfer tube according to claim 1, wherein the tube includes at least one welding seam extending in the longitudinal direction along the length of the tube.

19. A heat transfer tube having an inner surface, the inner surface being divided into at least two zones extending in a peripheral direction about the inner surface, the at least two zones being defined by a transition located therebetween and extending in a longitudinal direction along the length of the inner surface,

the inner surface of the tube including a plurality of fins extending at an angle of inclination with respect to the longitudinal axis of the tube, each of said fins extending across the at least two zones,

at least one of said fins having a first fin height at a first portion corresponding to a first one of the zones and

having a second different fin height at a second portion corresponding to an adjacent second one of the zones, the change in the fin height occurring at the transition of the at least one fin from the first one of the zones to the second one of the zones.

20. The heat transfer tube according to claim 19, wherein the fin heights of the portions of spaced adjacent separate ones of the fins corresponding to one of the respective zones are arranged in a periodic sequence.

21. The heat transfer tube according to claim 19, wherein the at least one fin has a first fin width for the first portion within the first one of the zones and a second different fin width at the second portion within the second adjacent one of the zones.

22. The heat transfer tube according to claim 19, wherein the tube includes at least a third zone extending in the peripheral direction about the inner surface and defined by first and second transitions with the adjacent zones that extend in the longitudinal direction along the length of the inner surface,

wherein the at least one fin having the first fin height within the first one of the zones and the second different fin height at the transition to the second adjacent one of the zones includes a third portion having a third fin height at the transition to and within the third zone.

23. The heat transfer tube according to claim 22, wherein the third fin height is different from the first fin height and the second fin height.

24. The heat transfer tube according to claim 20, wherein the heights of spaced ones of the fins in each of the zones are staggered between a portion of one of the fins having the first fin height and a portion of one of the adjacent separate fins having the second fin height.

25. The heat transfer tube according to claim 19, including a welding seam extending along the length of the tube in the longitudinal direction.

26. A heat transfer tube having an inner surface, the inner surface being divided into at least two zones, the two zones extending in a peripheral direction about the inner surface, the at least two zones being defined by a transition located therebetween and extending in a longitudinal direction along the length of the inner surface,

the inner surface of the tube comprising a plurality of parallel fins extending at an angle of inclination with respect to the longitudinal axis of the tube, each of said

fins extending across the at least two zones and at least about substantially the entirety of the inner surface, each of said fins having a first fin height and a first fin width at a first portion thereof corresponding to a first one of the zones and having a second different fin height and a second different fin width at a second portion thereof corresponding to an adjacent second one of the zones,

wherein the change in fin height and width occurs at the transition of the fin from the first one of the zones to the second one of the zones, the change in fin height and width reoccurring at further transitions to additional zones.

27. The heat transfer tube according to claim 26, wherein the fin heights corresponding to portions of spaced adjacent separate ones of the fins in each one of the zones, have a different fin height than the fin height of spaced and adjacent ones of the fins in the same zone.

28. The heat transfer tube according to claim 26, wherein the tube includes at least a third zone extending in the longitudinal direction along the length of the inner surface thereof, and,

the fins having the first portion with the first fin height and width within the first one of the zones and the second portion with the second different fin height and width at the transition to and in the second adjacent one of the zones, each of the fins including a third portion having a third fin height at the transitions to and within the third zone, the third fin height being different from the first fin height and the second fin height.

29. The heat transfer tube according to claim 26, wherein the inner surface of the tube includes a welding seam extending along the length of the tube in the longitudinal direction.

30. The heat transfer tube according to claim 26, wherein the plurality of fins are equal in length.

31. The heat transfer tube according to claim 26, wherein the fins are spaced equidistantly along the entire length thereof from adjacent ones of the fins.

32. The heat transfer tube according to claim 26, wherein the first fin height for the first fin portion is constant along the entirety of the first one of the zones and the second fin height for the second portion is constant along the entirety of the second one of the zones.
